INVENTOR:

PERCY A. CAMPBELL,
BY *Alexander S. Jones*,
HIS ATTORNEY.

UNITED STATES PATENT OFFICE

PERCY A. CAMPBELL, OF EAST CLEVELAND, OHIO, ASSIGNOR TO GENERAL ELECTRIC COMPANY, A CORPORATION OF NEW YORK

INCANDESCENT LAMP OR SIMILAR ARTICLE

Application filed March 17, 1927. Serial No. 176,225.

My invention relates to electric incandescent lamps and similar devices which comprise a filament supported within a bulb or other container. More particularly, my invention relates to devices of that character which are subjected during use to forces causing considerable vibration of the filament and its supports. The object of my invention is to render the filaments of such devices less responsive to forces tending to cause vibration thereof.

According to my invention means are provided for reducing the amplitude of vibration at the points of engagement of the leading-in and other supports with the filament. This may be accomplished, for example, by making said points of engagement intermediate rather than end points of the said supports, by weighting said points in some way or by a combination of such methods. The effect is to make nodes of said points or at least to make their amplitude of vibration much less than if they were at the ends of the supports or if the supports were unweighted.

In the drawings, Fig. 1 is an elevation of an electric incandescent lamp embodying one form of my invention; Fig. 2 is an elevation at right angles to that of Fig. 1; Fig. 3 is a fragmentary elevation; and Fig. 4 is an elevation at right angles thereto of a modification.

The incandescent lamp shown in Figs. 1 and 2 comprises the glass bulb 10 within which is supported a filament mount comprising a glass stem 11, a central glass rod 12, and the leading-in conductors 13 which are sealed at 14 in the stem 11 and are electrically connected to leading-in supports 15 each having one end embedded in the stem 11. The filament 16, preferably of the coiled type, is clamped at the intermediate points 17 and 18 to the said leading-in supports 15, which comprise loops which engage the filament and are clamped thereto. A number of other filament support wires 19 each has one end embedded in rod 12 and comprises a loop at an intermediate point which engages the filament 16. In this case the leading-in and other supports will have

their maximum amplitude of vibration at their free ends and a comparatively small amplitude at the points of engagement with said filament.

In the modification shown in Figs. 3 and 4, a somewhat similar effect is secured by weighting the leading-in supports adjacent to the points of engagement with the filament. Pieces 20 of metal such as nickel are united as by welding to the leading-in supports which are usually of nickel. The effect is to deaden the vibration which would ordinarily occur at these points. As shown, these points are near the end of the leading-in supports.

What I claim as new and desire to secure by Letters Patent of the United States, is:

A filament assembly for an incandescent lamp including a filament substantially in a plane at right angles to the axis of the lamp, a stem and a plurality of combined leading-in conductors and filament engaging supports extending from said stem, the free ends of said supports each projecting beyond the point of engagement with said filament to damp the vibrations of the filament.

In witness whereof, I have hereunto set my hand this 15th day of March, 1927.

PERCY A. CAMPBELL.
